SOLVENT EXTRACTION OPERATION

George T. Atkins, Jr., Highlands, Tex., assignor
to Standard Oil Development Company, a cor-
poration of Delaware

Application February 27, 1939, Serial No. 258,617

10 Claims. (Cl. 196—13)

The present invention relates to the art of solvent treating oils. The invention is concerned with a method of separating oils into their relatively more aromatic or hydrogen-poor constituents and into their relatively more paraffinic or hydrogen-rich constituents by means of selective solvents which have a preferential selectivity for the more aromatic or hydrogen-poor constituents as compared to the relatively more paraffinic or hydrogen-rich constituents. The invention especially relates to an improved process of economically recovering and purifying said selective solvent without the necessity of distilling the same.

In accordance with the present process, a feed oil, preferably a petroleum oil, is separated into three fractions, the first of which comprises a major quantity of highly aromatic components of greatest solubility in the primary solvent, the second of which comprises a major quantity of aromatic components of intermediate solubility in the primary solvent, while the third comprises a major quantity of paraffinic components of lowest solubility in the primary solvent. The first fraction comprising highly aromatic components is removed from the feed oil in a pretreating extraction zone by means of undistilled primary solvent. The second fraction comprising aromatic components of intermediate solubility in the primary solvent is removed from the pre-treated feed oil in a main treating zone by means of the primary solvent, the major portion of which has been recovered from the oil by re-extraction in a secondary treater with a secondary solvent having a preferential selectivity for the extract as compared to the primary solvent. The third fraction relatively paraffinic in nature is recovered from the main treater after a final extraction with a minor proportion of distilled primary solvent.

It is well known in the art to segregate petroleum oils into relatively more paraffinic or relatively hydrogen-rich fractions and into relatively more aromatic or relatively hydrogen-poor fractions by means of various selective solvents or solvent mixtures. The separation is usually accomplished by means of selective solvents of the class which have a preferential selectivity for the more aromatic type compounds as compared to the relatively more paraffinic type compounds. Solvents of this class are, for example, phenol, furfural, aniline, nitrobenzene, beta beta dichlor diethyl ether, and the like. These solvents are also employed together as well as in combination with other substances, as for example, substances

of the class of liquid normally gaseous hydrocarbons such as ethane, propane, butane, and the like. It is also known to use substances which have the ability to modify the selectivity and solvent power of the solvent, as for example, water, alcohols, glycols, and the like. The solvent, or solvent mixture, and the feed oil may be contacted in any suitable manner, as for example, by a multi-stage or batch operation. The usual process, however, is to contact the oil and solvent in a countercurrent tower treating operation in which the lighter component, usually the oil, is introduced in the bottom of the tower and the heavier component, usually the solvent, is introduced in the top portion of the tower. These phases flow countercurrently, intimately contacting each other, usually being assisted by various contacting and distributing means. The extraction operations are carried out under various temperature and pressure conditions depending upon the material being treated, the volume of solvent used per volume of oil being treated, as well as upon the quantity and quality of the products desired. In general, atmospheric pressure and a temperature between the melting point of the solvent and the temperature at which complete miscibility occurs between the oil and solvent are employed.

In these processes, the usual procedure is to separate the solvent rich or extract phase from the solvent poor or raffinate phase and to recover the oil from the solvent from the respective phases by distillation. This has not been entirely satisfactory since the specific heat and heat of vaporization of desirable solvents are relatively high, thus resulting in considerable heat loss and materially increasing the cost of operation. Furthermore, distillation causes a mechanical solvent loss as well as a loss due to thermal degradation of solvent. This is significant when it is considered that solvents having desirable selective characteristics are relatively expensive.

Various processes have been directed to the recovery of the selective solvent from the respective raffinate and extract phases in a more economical and practical manner. For example, it is known in the art to re-extract a solvent extract with a secondary solvent, as for example, naphtha, in order to remove the extract from the primary solvent. The secondary solvent containing the extract is then separated from the extract by distillation. This process effects considerable economies since the primary solvent loss is substantially decreased. The distillation cost is likewise decreased since the latent heat of the secondary solvent is less than the latent

heat of the primary solvent. This process, in the case of certain feed stocks, is not entirely satisfactory due to the fact that the secondary solvent does not completely remove from the primary solvent the highly aromatic and cyclic constituents. These constituents, therefore, are in some degree retained in the primary solvent, recycled to the countercurrent tower treating system, and, in part, redistributed to the raffinate oil which is very undesirable.

I have now discovered a process by which it is possible to separate a petroleum oil into relatively more paraffinic fractions and into relatively more aromatic fractions by means of a primary selective solvent and to re-extract the separated solvent extract phase with a secondary solvent in an efficient and practical manner. The process of my invention will permit the recovery of the primary solvent in an economical manner and will produce raffinate oil of satisfactory quality from all lubricating oil feed stocks customarily treated with selective solvents which are subsequently removed by distillation.

The process of my invention may be readily understood by reference to the attached drawings illustrating modifications of the same. Referring specifically to Figure 1 for purposes of illustration, it is assumed that the primary solvent is phenol, that the feed oil is a petroleum lubricating oil distillate, and that the secondary solvent is a close cut naphtha containing minimum amounts of those hydrocarbon components which are especially soluble in a primary solvent and having an average boiling point in the range from about 350° F. to 400° F. and which is termed "Paracyclo." The petroleum oil charge stock is introduced into pretreater tower 1 by means of feed line 2. This feed oil flows upwardly through tower 1 intimately contacting a relatively small percentage of undistilled total phenol which is introduced into tower 1 by means of feed line 3. Tower 1 contains suitable distributing and contacting means. Conditions on tower 1 are maintained to secure the formation of a solvent extract phase and a raffinate phase. The solvent extract phase is removed from tower 1 by means of line 4 and contains the most soluble components of the more aromatic type materials present in the original feed oil and a small percentage of the total primary solvent used in the process. This small percentage of total phenol is removed from the pretreater extract by means of distillation equipment 5. The distilled phenol is removed from distillation unit 5 by means of line 15 while the highly aromatic fraction is removed by means of line 16.

The undissolved oil phase is removed from tower 1 by means of line 6 and introduced near the bottom of the main extraction tower 7. The feed oil phase to tower 7 flows upwardly through the tower and contacts the major quantity of total undistilled phenol which is introduced into tower 7 by means of line 8. Tower 8 contains suitable distributing and contacting means. The raffinate phase is removed from tower 7 by means of line 9 and treated in a manner to remove the raffinate oil from the small amount of solvent. This is preferably accomplished by distillation. The extract dissolved in the primary solvent is removed from tower 7 by means of line 10 and passed into the top of re-extraction tower 11. The primary solvent phase flows downwardly through tower 11, contacting up-flowing paracyclo which is introduced into tower 11 by means

of line 12 and which has a preferential selectivity for the extract as compared to the primary solvent. The secondary solvent containing the extract oil is removed from tower 11 by means of line 13 and the undistilled recovered phenol is removed from tower 11 by means of line 14. The major proportion of the undistilled recovered phenol is introduced into tower 7 by means of line 8 while the minor proportion of the recovered phenol is introduced into tower 1 by means of line 3.

A further modification of my invention may be seen by reference to Figure 2. For the purpose of illustration, it is assumed that the feed oil is a lubricating oil distillate, the primary solvent is phenol, and that the secondary solvent is paracyclo. The lubricating oil is introduced into tower 20 by means of feed line 21. The feed oil flows upwardly through tower 20 and contacts a small percentage of undistilled phenol which is introduced into tower 20 by means of line 22. It is to be understood that the selectivity and solvent power of the primary solvent may be modified by the introduction of a solvent modifying agent. Thus, for example, the selectivity of the phenol may be modified by the introduction of water, preferably introduced at more than one stage, by means of line 23. Conditions are maintained on tower 20 to secure the formation of a raffinate phase and a solvent extract phase. The pretreater solvent extract consisting of a minor proportion of the undistilled solvent and the greater proportion of those most highly aromatic type materials present in the feed oil is removed from tower 20 by means of line 24 and introduced into pretreater extract stripper 25 in which phenol is removed from the extract by distillation. The pretreater extract is removed from pretreater extract stripper 25 by means of line 26 and the distilled phenol by means of line 46.

The undissolved oil phase from tower 20 is removed by means of line 27 and introduced in the lower part of tower 28. The feed oil to tower 28 flows upwardly through the tower and contacts in the initial stages the major proportion of total undistilled phenol which is introduced into tower 28 by means of line 29. Water or a similar solvent modifying agent may be injected into tower 28 by means of line 30. In the latter stages the up-flowing feed oil contacts distilled phenol which is introduced into tower 28 by means of line 31. The raffinate phase is removed from tower 28 by means of line 32 and taken to raffinate stripper 33 in which the phenol is separated from the raffinate by distillation. The solvent free raffinate is removed from raffinate stripper 33 by means of line 34 and the distilled phenol by means of line 46. The solvent extract from tower 28 is removed by means of line 35 and is introduced in the top of re-extraction tower 36. Prior to entry into tower 36, the solvent extract from tower 28 may be cooled by means of cooler 44 or may be diluted with water introduced into line 35 by means of line 45, or both, for the purpose of reducing the solubility of extract oil in the primary solvent.

The primary solvent phase flows downwardly through tower 36 and contacts up-flowing paracyclo which is introduced into tower 36 by means of line 37. The paracyclo extracts the oil from the phenol and is removed as secondary solvent extract phase by means of line 38. The secondary solvent extract phase is taken to extract

stripper 39 in which the secondary solvent is separated from the extract, preferably by distillation. The solvent-free extract is removed from extract stripper 39 by means of line 47 and the distilled solvent is removed by means of line 46. The major proportion of undistilled phenol is removed from tower 36 by means of line 40 and dried to the desired extent in drier 41. A minor proportion of the total phenol is removed from drier 41 and introduced into pre-treater tower 20 by means of line 22. The major proportion of the total phenol is introduced into extraction tower 28 by means of line 29. Phenolic water, recovered in drier 41, is preferably introduced into towers 20 and 28 by means of lines 23 and 30 respectively.

Distilled phenol from the respective strippers 25 and 33 and 39 is condensed and cooled and allowed to layer in phenol storage 43. The layer of distilled phenol is returned to the top of tower 28 by means of line 31. Normally, it is preferred to return all of the undistilled phenol from drier 41 to tower 28 by means of line 29 and to supply pretreater tower 20 with a solvent phase containing dissolved oil fractions of intermediate solubility through line 42 and 22 from tower 28. This solvent phase is preferably removed from tower 28 from a point near the pretreater oil feed inlet to tower 28.

30 The process of the present invention may be widely varied. It is preferred to use a primary solvent selected from the class of solvents which have a preferential selectivity for the relatively more aromatic or hydrogen-poor compounds as compared to the relatively more paraffinic or hydrogen-rich compounds. Primary solvents of this class are, for example, furfural, aniline, nitrobenzene, beta beta dichlor diethyl ether, sulfur dioxide, and the like, or mixtures of these. 35 The preferred primary solvent is phenol, the selectivity of which may be modified by means of a solvent modifying agent, such as water, which is preferably introduced at more than one stage.

40 The secondary solvent suitable for re-extracting the primary solvent extract may be any solvent which has a preferential selectivity for the extract as compared to the primary solvent. Preferred secondary solvents are highly paraffinic materials boiling in the range from about 200° F. to 600° F. and having a mid boiling point in the range from about 350° F. to 400° F. The preferred secondary solvents are those which have a low specific heat and a low heat of vaporization. A particularly desirable secondary solvent is a highly paraffinic naphtha boiling in the range from about 300° F. to 400° F. and containing minimum amounts of those hydrocarbons especially soluble in the primary solvent.

45 The temperature and pressure conditions maintained in the pretreater and in the extraction tower may widely vary depending upon the particular primary solvent being used, the oil being treated, as well as upon the quantity and quality of the products desired. For example, when employing phenol as the primary solvent, it is preferred to use atmospheric pressure at a temperature in the range from 100° F. to 250° F. The volume of primary solvent used per volume of oil will likewise depend upon the above-named factors. When using phenol, it is preferred to use from 1 to 4 volumes of phenol per volume of oil. The proportion of primary solvent used in the pretreater will likewise vary widely and will depend upon the particular conditions of 50 operation. When using phenol, for example, it

may be desirable to introduce as high as 60% of the total phenol into the pretreater, although, in general, it is preferred to introduce not over 50% of the phenol into the pretreater. In general, it is preferred to introduce not over 20% 5 of the total phenol into the pretreater.

The quantity of secondary solvent used per volume of primary solvent extract being treated will depend to a large extent upon the particular primary solvent being used and the character of 10 the oil being treated, as well as upon the secondary solvent employed. For example, when using phenol as the primary solvent and paracyclo as the secondary solvent, it is preferred to use from about $\frac{1}{2}$ volume to 2 volumes of paracyclo per 15 volume of oil being treated.

In processes in which distilled phenol is used in the main extraction tower to effect a final removal of the more aromatic constituents, it may be desirable to use as high as 60% phenol 20 based upon the volume of oil being treated. However, in general, the quantity of distilled phenol should be less than about 30% based upon the total quantity of primary solvent.

25 In order to more fully demonstrate the invention, the following examples are given which should not be construed as limiting the invention whatsoever.

EXAMPLE 1

30

A lubricating oil distillate from Coastal crude having a gravity of 21.7° A. P. I. was solvent extracted with phenol in accordance with the 35 process of the present invention.

The paracyclo solvent used for re-extraction was a blend consisting of 60% by volume of kerosene refined by extraction with liquid sulfur dioxide and 40% by volume of kerosene from Rodessa crude. This paracyclo solvent had the 40 following inspections:

TABLE 1

Gravity	° A. P. I.	50.0	45
ASTM distillation:			
I. B. P.	° F.	310	
F. B. P.	° F.	450	
50% at	° F.	360	50

The pretreater tower comprised two contact stages. The first stage received the oil feed stock, phenol solution from the oil feed stage of the main treater, and cycle oil precipitated from the second stage of the pretreater tower. The first discharged its oil phase to the main treater and discharged its phenol phase to the second stage of the pretreater. Phenolic water added to the second stage of the pretreater precipitated cycle oil which then entered the first stage as described above. The phenol solution from the second stage was distilled for the recovery of phenol and stripped pretreater extract.

The main treater comprised seven contact 65 stages. Distilled phenol flowed countercurrently to raffinate oil in the three final stages; undistilled phenol plus the phenol solution effluent from the three above-mentioned stages flowed counter-currently to the oil feed in the next 70 three stages. The seventh stage was fed with phenol layer from the oil feed stage and with phenolic water used to precipitate a cycle oil fraction. The cycle oil was returned to the oil feed stage. The phenol solution containing the 75

main extract was withdrawn from the cycle oil stage, cooled and charged to the re-extraction tower.

The operating temperature maintained on both stages of the pretreater tower was 155° F. The operating temperatures maintained on the primary tower were as follows:

TABLE 2

	Point of introduction of distilled phenol	° F 150
15	Point of introduction of undistilled phenol	° F 160
	Point of introduction of pretreated oil charge	° F 155
	Bottom of tower	° F 155

20 A temperature of 120° F. was maintained on the re-extraction tower. A phenol layer from the re-extraction tower was dried by flashing off phenolic water at an absolute pressure of 150 mms. at a temperature of 167° F. The distillate from the drier was cooled whereby layers of phenolic water, paracyclo, and phenol were obtained. The phenolic water was returned to pretreater and to the main treater in measured amounts. The paracyclo and phenol from the drier were combined with distillates of phenol and paracyclo from the raffinate and extract strippers. Raffinate and extract oils were freed of phenol and paracyclo by distillation under vacuum. The phenol and paracyclo distillates were combined, cooled, and the resulting liquid phases separated. The distilled phenol liquid phase was dried by heating to a temperature of 170° F. at an absolute pressure of 145 mms. The recovered paracyclo and dried distilled phenol 40 were measured and returned to the re-extraction tower and main treater respectively. Results of this operation are summarized in the following table:

The significant improvement obtained by use of the pretreater in combination with the main treater is illustrated by the lower neutralization value and higher color of the raffinate oil, as is evident from the comparison of Table 5 with Table 9. Furthermore, the results shown in Table 5 are not to be regarded as representing the maximum difference between the two methods of operation, or as representing the highest product quality obtainable by use of the pretreater, inasmuch as only two contact stages were used in the pretreater of Example 1 whereas the pretreater tower of a full scale commercial installation would contain a greater number of contact stages with the oil feed inlet at an intermediate point in the pretreater tower.

The present invention is not to be limited by any theory or mode of operation but only by the following claims in which it is desired to claim all novelty insofar as the prior art permits.

I claim:

1. Improved solvent treating process comprising contacting a mineral oil with a minor proportion of a primary solvent in an initial extraction zone under conditions to form a solvent extract phase and a raffinate phase, removing said solvent extract phase and separating said solvent therefrom by distillation, separating said raffinate phase and treating the same with the major proportion of the primary solvent in a secondary extraction zone, removing a raffinate phase from said secondary extraction zone and separating the solvent from the raffinate by distillation, removing a solvent extract from said secondary extraction zone and re-extracting the same in a tertiary extraction zone with a secondary solvent having a preferential selectivity for the extract as compared to said primary solvent, removing primary solvent from said tertiary extraction zone and returning a minor proportion to said primary extraction zone and a major proportion to said secondary extraction zone, removing from said tertiary extraction zone a secondary solvent phase containing mineral oil extract, separating said secondary solvent from said oil extract by distillation and returning said secondary solvent to said tertiary extraction zone.

2. Process in accordance with claim 1 in which said primary solvent is selected from the class of solvents having a preferential selectivity for the more aromatic type compounds as compared to the more paraffinic type compounds and in which said secondary solvent is a solvent which has a preferential selectivity for petroleum oil compounds as compared to primary solvents.

3. Process in accordance with claim 1 in which said primary solvent is phenol and said secondary solvent is a highly paraffinic petroleum naphtha boiling in the range from about 300° F. to 400° F. and which contains minimum amounts of constituents which are soluble in said phenol at operating temperatures and pressures.

4. Process in accordance with claim 1 in which

said minor proportion of primary solvent is from 20% by volume based upon the oil feed to 45% of said major proportion of primary solvent and said major proportion of primary solvent comprising from about 100% to 400% of solvent 5 based upon the oil feed.

5. Process in accordance with claim 1 in which an anti-solvent is introduced into the primary and secondary extraction zones, said anti-solvent being secured by distillation from the primary 10 solvent phase withdrawn from said tertiary extraction zone.

6. Improved solvent treating process comprising contacting a petroleum oil with a primary solvent phase in an initial extraction zone under conditions to form a solvent extract phase and a raffinate phase, removing said solvent extract phase and recovering the solvent by distillation, separating said raffinate phase and treating the same in a secondary extraction zone with the 20 major proportion of said primary solvent, separating the raffinate from said secondary extraction zone and recovering the primary solvent therefrom by distillation, removing a minor proportion of said primary solvent phase from said 25 secondary extraction zone and introducing the same into said initial extraction zone, separating the solvent extract phase from said secondary zone and re-extracting the same in a tertiary zone with a secondary solvent having a preferential 30 selectivity for the extract as compared to said primary solvent, separating said primary solvent and returning to said secondary extraction zone, separating a secondary solvent extract phase from said tertiary zone and recovering the solvent 35 therefrom by distillation, returning said recovered secondary solvent to said tertiary zone.

7. Process in accordance with claim 6 in which said minor proportion of said primary solvent phase is removed from said secondary extraction 40 zone from a point adjacent to the point at which the raffinate from the initial extraction zone is introduced into said secondary extraction zone.

8. Process in accordance with claim 6 in which said primary solvent is phenol and in which 45 secondary solvent is a highly paraffinic petroleum oil boiling in the range from about 300° F. to 450° F. and containing minimum amounts of components which are especially soluble in the phenol.

9. Process in accordance with claim 6 in which the amount of primary solvent contacted with the oil in said initial stage is from 20% of solvent based upon the oil feed to 45% of the primary solvent introduced into said secondary extraction zone and in which the quantity of primary solvent contacted with the oil in said secondary zone is 100% to 400% of solvent based upon the oil.

10. Process in accordance with claim 6 in which said raffinate from said secondary stage is contacted with distilled primary solvent prior to removal from said secondary zone.

GEORGE T. ATKINS, JR.
